UNITED STATES PATENT OFFICE

2,447,242

WIRE STRAIGHTENER

Edwin T. Fredrich, Walter Barr Mitchell, and
Frank E. Buyken, Seattle, Wash.

Application March 26, 1946, Serial No. 657,244

4 Claims. (Cl. 140—147)

1

The present invention relates to a novel and improved wire straightener such as lends itself adaptable to straightening steel wire but which is expressly designed and adapted to remove kinks, curls, and twists from so-called all steel wire leaders such as are used by sport and commercial fishermen.

More specifically, the invention relates to a simple and practical double jaw wire grip which is applied, removed and operated by hand, said grip being slid back and forth in a manner to "iron out" twists and kinks without removing the spoon, hooks, or plug.

In carrying out the principles of the invention I provide a simple stainless steel, rust-proof device of general U-shaped form, the bight or connective portion being fashioned into a spring and the end portions constituting the aforementioned jaws, said jaws having a plurality of co-acting indentations, the latter being of circular concavo-convex form and constituting wire tracking and straightening elements.

Ordinarily fishermen, after landing a fish with an all steel wire leader find that it is bent and twisted and often snarled into such a shape that it requires replacement with a new leader and this, of course, is time consuming and often needlessly expensive. It is therefore the purpose of the present invention to provide a simple and expedient hand type accessory which will effectively straighten the leader from end to end, this in a feasible and reliable manner.

Other objects, features and advantages of the invention will become more readily apparent from the following description of the accompanying illustrative drawings.

In the drawings, wherein like numerals are employed to designate like parts throughout the views:

Figure 1 is a side elevational view of a wire straightener constructed in accordance with the principles of the instant invention.

Figure 2 is a vertical sectional taken approximately on the irregular lines 2—2 of Figure 1, looking in the direction of the arrows.

Figure 3 is a view like Figure 1 showing the manner in which the wire straightener is employed in conjunction with the partially twisted leader, and

Figure 4 is an end view of Figure 3 observing same in a direction from right to left.

Referring now to the drawings by distinguishing reference numerals it will be seen that the wire straightener, as a unit, is denoted by the numeral 6. As before indicated it is preferably

2

made from stainless steel and is of the approximate size depicted in the drawings. In carrying out the invention, a small plate or sheet of steel is employed and is bent between its ends into a U-shaped form, this to define a pair of opposed substantially flat rectangular jaws or grips 7 and 8. The free longitudinal edges of said jaws are bent and flared laterally outward into diverging form as indicated at the points 9. The connective or bight portion is especially bent and formed into a spring 10. This is of such resiliency as to normally urge and spread the jaws 7 and 8 apart. At median points along the transverse ends 11 and 12 I provide outwardly pressed bends 13 and 14 and the bends 13 are aligned with the bends 14. These so-called bends constitute shallow V-shaped guides to pilot and seat the leader or wire 15 between the jaws. Or to put it otherwise, these bends also function as seats and guides and are seated on the wire shown in Figure 3 in order to permit the entire device 6 to be slid back and forth in relation to the wire.

The respective jaws 7 and 8 are provided with a plurality of circular indentations, these of concavo-convex form. Some of the indentations are large and the others small. Each jaw may be said to embody upper and lower series or sets of indentations 19 and 20, the upper series being denoted at 16 and the lower series at 17. It is obvious that the indentations on the respective jaws 7 and 8 interfit or nest together to hold the jaws relatively fixed when they are pressed by hand into contact with each other. Likewise, the indentations are staggered in alternating relationships and present the desired cam-like tracking and straightening surfaces when the device is in use. Reference being had to Figure 3, we see the device in use and also observe kinks 18 at the left-hand end of the wire.

In practice it is obvious that the wire is placed between the jaws and is nested in the guide bends 13 and 14 in the manner shown. The fish hook (not shown) on the outer end of the leader is anchored on any appropriate or suitable obstacle thus securing one end of the wire fixedly in place. The other end of the wire is held in one hand and the device is poised and placed in position over the wire, this as illustrated. It is then grasped and pulled first towards the operator and then pushed back toward the anchored hook. A slight pressure on the straightener jaws is required to set the wire as it runs between the tracking and straightening indentations 19 and 20. This gives a curved action which automati-

cally straightens the wire and renders it ready to be again used.

In working out this device, we found that it requires a curve to straighten a curve and this accounts for the particular arrangement and positioning of the tracking and straightening elements.

In conclusion it is perhaps desirable to stress that the elements or bends which go to make the group 16 are denoted by the numerals 19 and those which go to make up the group 17 are denoted by the numerals 20.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

We claim:

1. A wire straightener of the class described comprising a U-shaped resilient metal device embodying a pair of opposed jaws between which the wire is adapted to occupy a position for straightening, said jaws being provided with a plurality of indentations, said indentations being of circular concavo-convex form and certain indentations of the respective jaws nesting into one another when the jaws are pressed flat together, said indentations on the respective jaws being arranged in a manner to form substantially parallel inner and outer rows and being in staggered relation to each other with a maximum free space transverse to the rows between the periphery of any indentation in one row and the periphery of the adjacent indentation in the other row slightly less than the diameter of the wire which is to be drawn between the jaws and coacting staggered peripheral portions of the indentations.

2. A wire straightener of the class described comprising a substantially U-shaped member including a bight portion fashioned into a springy hand-grip and further embodying end portions formed into substantially flat plate-like jaws, the free longitudinal edges of said jaws being flared outwardly into divergent relationship, the transverse ends of the respective jaws having opposed pairs of V-shaped bends, the bends at one end of the U-shaped member being lined up with the V-bends at the opposite end of said member and constituting wire seating and piloting guides for the wire which is to be straightened, and said jaws being provided with a plurality of bosses arranged in a manner to form substantially parallel inner and outer rows in line with said V-bends and being in staggered relation to each other with a maximum free space transverse to

the rows between the periphery of any boss in one row and the periphery of the adjacent boss in the other row slightly less than the diameter of the wire which is drawn between the jaws and coacting staggered peripheral portions of said bosses.

3. A wire straightener of the class described comprising a U-shaped relatively small metal device adapted to be held in the hand of the user and embodying a pair of opposed jaws between which the wire to be straightened is adapted to pass, said jaws being provided with wire contacting and kink removing bosses arranged in a manner to form substantially parallel inner and outer rows and being in staggered relation to each other with a maximum free space transverse to the rows between the periphery of any boss in one row and the periphery of the adjacent boss in the other row slightly less than the diameter of the wire which is to be drawn between the jaws and coacting staggered peripheral portions of said bosses.

4. A wire straightener of the class described comprising a U-shaped resilient metal device to be held in the hand of the user and embodying a pair of opposed resilient jaws between which the wire is adapted to occupy a position for straightening, said jaws being provided with a plurality of indentations, said indentations of the respective jaws fitting into one another when the jaws are pressed, by hand, firmly against one another, said indentations on the respective jaws being arranged in a manner to form substantially parallel inner and outer rows and being in staggered relation to each other with a maximum free space transverse to the rows between the periphery of any indentation in one row and the periphery of the adjacent indentation in the other row slightly less than the diameter of the wire which is to be drawn between the jaws and coacting staggered peripheral portions of the indentations.

EDWIN T. FREDRICH.
